[57] CLAIM

The ornamental design for a stand for exhibiting articles, as shown and described.

DESCRIPTION

FIG. 1 is a perspective view of a stand showing my invention. The dotted line shows an article mounted on the stand for illustrative purposes only and forms no part of the claimed design;

FIG. 2 is a front elevation view thereof;

FIG. 3 is a left side elevational view, the right side being a mirror image thereof;

FIG. 4 is a rear elevation view thereof;

FIG. 5 is a top view thereof;

FIG. 6 is bottom view thereof; and,

FIG. 7 is an alternative view of the embodiment shown in FIG. 1.
